Patented Dec. 7, 1971

222,705

OPAQUE IMAGE PROJECTOR OR THE LIKE

Gerald G. Mayer, Los Angeles, Calif., assignor to
Kopykake Enterprises

Filed Apr. 2, 1970, Ser. No. 22,212

Term of patent 14 years

Int. Cl. D16—02

U.S. Cl. D61—1

Fig. 2

Fig. 3

Fig. 1

Fig. 6

FIG. 1 is a right side elevational view of an opaque image projector or the like showing my new design; and FIG. 2 is fragmentary front perspective view thereof;

FIG. 3 is a fragmentary left side elevational view thereof;

FIG. 4 is a fragmentary top plan view; and

FIG. 5 is a fragmentary rear elevational view; and

FIG. 6 is a front elevational view.

The base portions of the invention have been omitted for convenience of illustration in FIGS. 2, 3, 4 and 5. The top portion of the supporting pole has been omitted for convenience of illustration in FIGS. 1, 2, 3, 5 and 6.

I claim:

The ornamental design for an opaque image projector or the like, substantially as shown and described.
